UNITED STATES PATENT OFFICE.

DANIEL J. O'CONNOR, CHARLES A. NELSON, AND CARL NAHABED, OF NEW YORK, N. Y.,
ASSIGNORS TO TWISTED WIRE & STEEL CO., A CORPORATION OF NEW YORK.

WIRE-STRETCHER.

1,400,093.

Specification of Letters Patent. Patented Dec. 13, 1921.

Application filed December 24, 1920. Serial No. 432,990.

To all whom it may concern:

Be it known that we, DANIEL J. O'CONNOR, CHARLES A. NELSON, and CARL NAHABED, all citizens of the United States, and 5 residents of the city, county, and State of New York, and whose post-office address is 437 Eleventh avenue, New York city, have invented certain new and useful Improvements in Wire-Stretchers, of which the following is a specification.

Our invention relates to that class of stretchers in which the free ends of box-strapping, flat or round, or other fastening material, are drawn together under desired 15 tension so that they may be securely fastened and thereby hold firmly the box, or other package or receptacle together during transportation.

The object of our invention is to simplify 20 the construction of such stretchers, and to provide a stretcher of strong, durable and effective character.

One form of our invention is shown in the accompanying drawings in which:—

25 Fig. 1, is a side elevation.

Fig. 2, is a top plan.

Fig. 3, is a longitudinal section looking in the direction of the arrows 3, 3, of Fig. 1.

Fig. 4, is a similar view showing the 30 pawls engaging the rack.

Fig. 5, is a cross section on line 5—5, of Fig. 1.

Fig. 6, is a cross section on line 6—6, of Fig. 1.

35 Same letters indicate similar parts in the different figures.

In the form shown, A and B are two independent gripping carriages and a rack-plate C is secured at one end to carriage A and 40 adapted to be drawn through carriage B by multiple pawl D, E, as required by moving the handle F. The result of this action is to cause the two carriages to approach each other and tighten the flat or round wire 45 gripped by them,—that carriage moving which is under the lesser tension and the other carriage remaining practically stationary. That is to say:—the rack-plate C and its attached carriage A will be drawn

50 toward the carriage B if the tension of carriage B is greater than that of carriage A, or the carriage B will be fed along the rack-plate C toward carriage A, if the tension of carriage B is less than that of carriage A.

55 A. Each of the two carriages A, B, has a

smooth bottom, preferably, adapted to rest on the box or other article to be strapped, and to slide thereon readily.

Projecting laterally from each carriage is a holding plate a, b, respectively upon 60 which the wire or band to be stretched is placed and where it is gripped by a suitable gripping device. This device, as shown, is in the form of a cam-lever F, F, pivoted to the carriage, at f, f, but it is to be understood that various other ways of gripping the wire or band may be employed if preferred, our invention relating more particularly to the manipulation of the rack-plate which tightens the strain put upon the 65 band or wire by the devices which hold the same to the respective carriages. For the sake of clearness carriage A may be called the rack-carriage, and carriage B, the pawl-carriage, thus expressing their individual functions.

We are aware that wire-stretchers exist in which the tightening is brought about by the use of two gripping carriages and a sliding rack but never, so far as 70 we are aware by such a simple, strong and efficient drawing mechanism as our multiple pawl device with which carriage B is equipped. By this device many of the elements heretofore employed, such 75 as pinions meshing with the rack, springs, ratchet-wheels, etc., are dispensed with the engagement of the multiple pawl being direct with the teeth of the rack-plate itself. And this multiple pawl arrangement is operated by a single handle G.

To accommodate the multiple pawl arrangement and allow a perfect freedom of action, the pawl-carriage B, is provided with a forward block H, through which the rack-plate passes as through the carriage itself and which is integral with or securely attached to the carriage B by the bridge I, as by screws c, c, (Fig. 2).

The handle G is pivoted, as at d, to the 100 bridge I, and the short arm is curved as shown to secure freedom of swing in a comparatively small space. To this handle are pivoted at e, a pair of parallel driving pawls K, which have the double function of alternately engaging the teeth of the rack-plate C, when in the position shown in Fig. 4, and of operating the corresponding holding pawl of which there are two, L, L, pivoted to the block H, at g. The upward motion 105 110

of these holding pawls is limited by the stop *h*, in the block *H*.

The operation of our improved stretcher will, we think, be readily understood by those skilled in such matters and is briefly as follows:—

While the device is in its inoperative position as shown in Fig. 3, the free ends of a wire or box-strap which has been placed 10 around the box or other article to be strapped, are inserted under the cam levers *F*, *F*, on their respective holding plates *a*, *b*. The handle *G* is then thrown toward the position shown in Fig. 4. This causes one 15 of the driving pawls to displace its holding pawl from the position shown in Fig. 3 into that shown in Fig. 4, where it is prepared to hold the rack against any back-pull of the stretching wire or band. By its continued movement the driving pawl has 20 drawn the rack-plate the distance corresponding to the number of teeth which represents the swing to which said pawl was adjusted and hold fast as shown in said 25 Fig. 4, until the strain is relieved by the companion driving pawl going through the same set of motions. Once released, the first driving pawl is raised to the position of Fig. 3, while the other pawl holds the 30 rack till released in turn. It will thus be seen that the two sets of pawls, one driving

and one holding, work alternately until by their successive action the stretching has been brought to the desired tension. The strap-ends are then secured by any desired 35 method of sealing and the stretcher assumes a position which permits the free sliding of the rack-plate to its original position for another tightening operation.

We claim:

1. A wire-stretcher which is provided with a multiple pawl arrangement which consists of a pair of driving pawls adapted to operate alternately, and a pair of holding pawls each of which is adapted to be operated by its corresponding driving pawl 40 during the tightening operation.

2. In a wire-stretcher a multiple pawl arrangement which comprises a pair of driving pawls acting alternately in engaging a 45 rack-plate, a pair of holding pawls operated successively by their respective driving pawls, and a rack adapted to be moved and held alternately by each set of driving and holding pawls.
